Weed & Gray

UNITED STATES PATENT OFFICE.

ALAN R. FERGUSSON, OF BUFFALO, NEW YORK.

RAIL CONNECTER FOR TOY RAILWAYS.

Original application filed September 27, 1922, Serial No. 590,781, now Patent No. 1,452,370, dated April 17, 1923. Divided and this application filed April 3, 1923. Serial No. 629,739.

To all whom it may concern:

Be it known that I, ALAN R. FERGUSSON, a citizen of the United States, residing at Buffalo, in the county of Erie and State of New York, have invented certain new and useful Improvements in Rail Connecters for Toy Railways, of which the following is a specification.

- This invention relates to rail connecting or clamping devices for toy or miniature railways, and is a division of my copending allowed application for toy railway, Serial No. 590,781, filed September 27, 1922, now Patent No. 1,452,370, dated April 17, 1923.
- An object of this invention is to provide a clamping device particularly adapted for the purpose of detachably or releasably clamping or connecting together a rail and a supporting tie of a toy track section.
- A further object of this invention is to provide an efficient and easily manipulated clamping device having a semi-circular channel or gutter member for clamping a cylindrical body or wire rail to its supporting means.

- A further object of this invention is to provide an efficient and relatively cheap connecting or clamping device for releasably connecting together a pair of cylindrical members such as a cylindrical wire rail and tie, preferably located one at right angles to the other.

- Other objects of this invention will appear in the following description and appended claims, reference being had to the accompanying drawings forming a part of this specification wherein like reference characters indicate corresponding parts in the several views and wherein Fig. 1 is a plan view partly broken away illustrating my improved connecting device as applied to a toy railway section; Fig. 2 is a perspective view of the connector or clamping device; Fig. 3 is a fragmentary perspective view illustrating the lower part of the device and Fig. 4 is a detail perspective view illustrating the parts of the device.

- Before explaining in detail the present improvement and mode of operation thereof, I desire to have it understood that the invention is not limited to the details of construction and arrangement of parts which are illustrated in the accompanying drawings, since the invention is capable of other

embodiments, and that the phraseology which I employ is for the purpose of description and not of limitation.

The present improved clamp or clip device is adapted for use particularly with a wire formed toy railway section and as shown in Fig. 1 is especially adapted for the purpose of detachably connecting a cylindrical and preferably a wire formed rail such as a power rail to a cylindrical cross tie, such as a wire formed tie.

For the purpose of illustrating the particular application or use of the present invention a wire formed toy railway section is illustrated in Fig. 1, the section comprising wire formed supporting ties 9 having a pair of wire formed traction rails 10 secured thereto in spaced relation. A detachable wire formed power or third rail 11 is adapted to be releasably connected to one of the cross ties 9 by means of my improved connecting or clamping device, so that by means of this device a cylindrical wire or body is releasably connected to a cylindrical wire or body extending transversely thereto. The clamp in its preferred form comprises preferably a pair of substantially similar members insulated one from the other and interlocked in inverted relation through the medium of the insulation. Each of these members comprises a body member 12 preferably cut to the required shape from sheet metal and bent up or coiled to form a pair of curved side walls 13 and 14. These curved walls are open at the top so that the longitudinal edges 15 and 16 are spaced apart throughout the length of the device.

The side walls 13 and 14 form a channel or gutter into which the wire 11 may be inserted, and it will be noted that the side walls and base of the member form substantially a semi-circular channel. Furthermore, the width of the longitudinal opening at the top of the channel or gutter is somewhat less than the diameter of the channel, which has an inner diameter substantially the same as the diameter of the cylindrical or wire rail 11.

As a result of this construction when the wire or cylindrical rail is pressed through the opening at the top of the clamp the side walls 13 and 14 will spread or spring apart to permit the wire to be seated in the channel. Thereupon the semi-circular walls of

the clamp or clip will spring back into place and encircle or embrace the cylindrical wire or body.

It will thus be noted that the semi-circular walls form substantially spring jaws adapted to spring open and resiliently grip the cylindrical body or wire. The latter may be easily detached from the jaws or walls 13 and 14 by pulling the wire and clip apart, 18 the jaws springing open during this operation, which is permitted by the fact that the jaws or walls 13 and 14 embrace the wire only to a point a fraction beyond its center line. Furthermore, since the semi-circular 23 walls or spring jaws of the clamp embrace or encircle only a fraction more than one half of the circumference of the wire rail 11, the wheel or roller on the engine will travel over the top of the wire without hitting or contacting with the clamp walls 13 and 14.

Each of the clip members forming the device terminate in projecting portions 17 which are bent under to form hook shaped 28 tongues 18. These bent tongues 18 are securely clamped to a piece of insulating material 19, and the gutters or clip members are positioned at right angles to each other, the upper member A having the channel opening at the top thereof and the lower gutter or member B being in inverted position with relation to the upper member A and having the channel opening at the bottom thereof.

It will of course be noted that the inverted 33 clip member B is adapted to be releasably connected to the cylindrical or wire cross tie 9, the latter being sprung into the channel of the lower gutter member B, while the third rail 11 is sprung into the channel formed by the upper gutter member A.

Each semi-circular channel of the inverted parts A and B encircle sufficiently less of the cylindrical wire 11 or 9 so as to permit the walls or jaws of each gutter to spring 45 open slightly when the wire is forced in, a releasable spring gripping connection thus being provided in each instance. It will be noted that the side edges of the insulating strip 19 are notched at 20 so as to form recesses for receiving the bent tongues 17-18 and preventing any substantially relative movement, the insulating member 19 forming a means through the medium of which the clip members A and B are interlocked and insulated one from the other.

The end clip 21 illustrated in Fig. 1 for the purpose of joining the opposed ends 22 and 23 of a pair of wire rails, also comprises a body portion bent up to form a pair of 60 substantially semi-circular side walls 24 and 25. In this instance, the end 22 of one wire is secured at 26 as by spot-welding within the semi-circular channel formed by the walls 24 and 25. This channel is sufficiently long to permit the end 23 of the opposite

rail to be sprung into position therein, thus providing a resilient gripping clamp.

One end of the clamp 21 is provided with a bent tongue 27 which is adapted to hook over the edge 28 of the rail plate 29, a strip of insulating material 30 being interposed between the clamp and the wire rail and ends 22 and 23.

It will be understood that the curved walls 13 and 14 of upper gutter member A may be of any desired height so as to hold a cylindrical body therebetween, and may extend to any desired height beyond the center line of the channel. If it is desired to permanently hold a cylindrical body between the curved side walls, the same may extend to a somewhat greater height and the wire or cylindrical body inserted or threaded endwise into the channel between the semi-circular side walls.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A clamping device for clamping a wire rail of a toy railway and comprising a sheet metal body member bent to form a pair of substantially semicircular expandable and contractible walls, and means located at the bent portion thereof for securing it in position.

2. A clamping device for clamping a wire rail of a toy railway and comprising a sheet metal body member having a pair of expandable and contractible side walls forming a semicircular channel having an opening at the top of less width than the diameter of said channel, and means at the bottom of said channel for securing it in position.

3. A clamping device for clamping a wire rail of a toy railway and comprising a body member bent to form a pair of resilient substantially semicircular walls having free edges projecting toward each other and spaced apart, said body member having at the bent portion thereof means for securing it in position.

4. A clamping device for clamping a wire rail of a toy railway and comprising a body member bent to form a pair of resilient substantially semicircular walls having free edges projecting toward each other and spaced apart, said body member having at the bent portion thereof means for securing it in position and comprising a pair of opposed hook forming members.

5. A clamping device for clamping a wire formed rail and tie of a toy railway together and comprising a pair of clip members connected together back to back and each having a similarly formed gutter whereby said gutters are located in inverted relation, one of said gutters having spring walls for gripping a rail or tie. 45
6. In a device of the class described the combination of a pair of clip members connected together and having each a gutter, and insulating means through the medium of which said members are rigidly interlocked. 50
- 15 7. In a device of the class described the combination of a pair of clip members connected together and having each a gutter, and insulating means for connecting said members together in inverted relation. 55
- 20 8. A rail connector for toy railways comprising a sheet metal member bent to form resilient side walls having spaced free edges adapted to grip a wire rail below the top thereof, said member having means located 60 at the bent portion thereof for securing it in position. 65
9. A rail connector for toy railways comprising a sheet metal member bent to form resilient side walls having spaced free edges adapted to grip a wire rail below the top thereof, said member having at opposite ends thereof a pair of clip forming portions for securing it in position. 70
10. A device of the class described comprising a pair of similar substantially semi-circular gutter members, insulating means located between said members, and said members having parts thereof bent to embrace said insulating means. 75
- 40 11. A device of the class described comprising a pair of similar substantially semi-circular gutter members positioned in inverted relation, insulating means located be- 80
- tween said members, and said members having parts thereof bent to embrace said insulating means. 85
12. A device of the class described comprising a pair of substantially semi-circular gutter members extending one transversely to the other and insulating means for connecting said members together. 90
13. A device of the class described comprising a pair of substantially semi-circular gutter members extending one transversely to the other and insulating means for connecting said members together, one of said members having a longitudinal opening at the outer part thereof and of less width than the diameter of the gutter member. 95
14. The combination of a clamp member comprising a substantially semi-cylindrical gutter, and an insulating strip, said gutter terminating in a projecting portion bent to embrace an edge of said strip. 100
15. The combination of a pair of transversely located clamp members located one above the other, and insulating means thru the medium of which said members are interconnected. 105
16. A rail connector comprising a body member having a pair of opposed edges bent in one direction to form a channel, and having a pair of opposed edges bent in the opposite direction to form a channel having resilient walls. 110
17. A rail connector having a pair of inverted gutter portions extending one transversely to the other, one adapted to be connected to a rail and the other to a cross tie, and one or both of said gutter portions having spring side walls. 115

Signed at Buffalo, New York, this 28th day of March 1923.

ALAN R. FERGUSSON.
